CLAIM

The ornamental design for a traction recovery track board, as shown and described.

DESCRIPTION

FIG. 1 is an upper perspective view of the traction recovery track board showing my new design;

FIG. 2 is a top plan view thereof;

FIG. 3 is a bottom plan view thereof;

FIG. 4 is a side elevation view thereof;

FIG. 5 is an opposite side elevation view thereof;

FIG. 6 is an end elevation view; and,

FIG. 7 is an opposite end elevation view.

The broken lines in the figures show portions of the invention that form no part of the claimed design.
